FILLING OR PACKING MATERIAL

Clarence A. Herbst, Chicago, Ill., assignor to
 Economy Fuse and Manufacturing Company,
 Chicago, Ill., a corporation of New York

Application February 10, 1932, Serial No. 591,964

18 Claims. (Cl. 200—131)

The present invention relates to filling or packing materials, and more particularly to filling or packing materials adapted for use in electrical fuses.

5 Among the objects of the present invention is to provide a novel filling or packing material adapted for use in packing articles, objects or elements to prevent these articles and the like from becoming displaced when moved or subjected to impacts and shocks which might be harmful or cause damage thereto.

Another object within the purview of the present invention is to provide a novel packing or filling material adapted to surround articles, and 10 the like, which includes an aggregate of coarse particles, the voids of which are substantially filled with an aggregate of finer particles which interlock with the coarser particles to prevent their shifting which might cause damage to or injure the article or the like surrounded thereby.

20 Still another object of the present invention is to provide an electrical fuse in which novel means is provided for effectively holding the fusible element therein against lateral displacement.

In electrical fuses carrying a fusible element between terminals provided therein, it has been found that when the same is packed or surrounded by a filling material in which the particles thereof are substantially of uniform diameter, there is a tendency for these particles to shift, thereby reducing the bulk so as to expose a substantial portion of the fusible element and to likewise cause a lateral shifting or displacement of this element.

It is therefore an object of the present invention to provide a novel filling material in which the particles thereof are prevented from shifting, which would cause a shifting or lateral displacement of the fusible element which they surround.

The present invention contemplates the idea of providing a filling material for electrical fuses or the like, comprising a coarse aggregate, the 45 voids of which are filled by particles of a finer aggregate, these smaller particles of the finer aggregate tending to hold the particles of coarser aggregate in their proper association with the fusible element, or other object and the like, 50 whereby the same is effectively held against lateral shifting or displacement. More specifically, the present invention is directed toward the providing of a filling material in which the coarse and fine aggregate comprises particles of some suitable granular material.

Other objects, features, capabilities and advantages are comprehended by the invention, as will later appear and as are inherently possessed thereby.

Referring to the drawing:

Figure 1 is a view in cross section of an electrical fuse made in accordance with the present invention;

Figure 2 is a diagrammatic sketch of a filling material comprising coarse particles only;

Figure 3 is a diagrammatic sketch similar to that shown in Figure 2 of the drawing and disclosing the shifting of this coarse material when used as a filler;

Figure 4 is a diagrammatic sketch of a filling material formed in accordance with the present disclosure; and

Figure 5 is a view in cross section taken in the plane represented by line 5—5 of Figure 1 of the drawing.

Referring now more in detail to the drawing, a filling material made in accordance with the present invention is shown in connection with an electrical fuse comprising a tubular casing 2 of any desired material, such as fiberboard or the like, the ends of this tubular casing being closed by the caps 4 and 6 which may be suitably secured in any desired manner to the casing 2. Each of the caps 4 and 6 is similar in construction and is formed with an opening 8 adapted to receive the end of a fusible element 10 which extends between these caps and may be secured thereto, as by soldering the ends thereof in the openings of these caps.

In order to prevent lateral displacement of the fusible element 10, the space around the fusible element 10 is filled with a filler comprising a coarse aggregate 12 which may be of any desired material such as a granular substance, the voids between the particles of this coarse aggregate being filled with one or more particles 14 of a finer aggregate.

As clearly shown in Figure 2 of the drawing, a filling material merely comprising a plurality of particles of a coarse aggregate 16 when placed within the casing 2 of an electrical fuse such as shown, will compact and settle, whereby the particles of the coarse aggregate will tend to shift upon one another and into a position as shown in Figure 3 of the drawing. Any tendency toward the relative shifting of these coarse particles, when the same are around the fusible element 10, tends to cause a lateral displacement of one or more portions of the fusible element 10 and to cause an extenuation of these laterally

displaced portions, thereby reducing or tending to reduce the cross-sectional area thereof. Any reduction in the cross-sectional area of the fusible element 10 will result in a decrease in its capacity for carrying the electrical currents for which it was originally designed, and were the same used in a circuit carrying this current, the same would blow. However, when the voids or interstices between the particles of the coarse aggregate are filled with particles of a finer aggregate, these smaller and finer particles act to interlock the particles of the coarser aggregate, thus preventing relative movement or shifting of the same.

15 From the above disclosure it will be quite apparent that the present novel filling or packing material is particularly adapted for protecting the fusible element of an electrical fuse, as for example, when this fuse is subjected to impact as when the same is put into place, or when shipped or moved from place to place. It is, of course, understood, however, that a fusible element is merely representative of any other object, article, or member which it is desired to protect against displacement which would be harmful or injurious thereto and, accordingly the present invention contemplates the idea of providing novel means for effectively maintaining an object, article, or the like, in a given position once the same has 20 been packed or surrounded in accordance with the present invention. Therefore, articles or objects may be packed for shipment or moving within the scope of the present invention.

It will be clearly seen, of course, that the 35 present invention includes the idea of providing a packing or filling material which is preferably of granular particles, the desideratum being to provide an aggregate which has a specific gravity equal to the specific gravity of the particles forming the same. Although it is not practically possible to provide an aggregate meeting this ideal situation or condition, it is, nevertheless, possible to increase the specific gravity of a given mass or aggregate of coarse particles by incorporating finer particles, thus filling the voids or interstices thereof so as to form an aggregate which has a specific gravity more nearly approaching the specific gravity of the individual particles.

50 In preparing an aggregate for the uses above set out, it has been found that a material having a mixture of about 70% 10-20 mesh filler, 5% 30-40 mesh filler and 25% 50-60 mesh filler produces a filling material of maximum specific gravity. This filling material therefore comprises an aggregate of which 70% thereof will pass a 10 mesh screen but will remain on a 20 mesh screen; 5% of which will pass a 30 mesh screen but will remain on a 40 mesh screen; and 25% 55 of which will pass a 50 mesh screen but will remain on a 60 mesh screen. Although an aggregate mixed in accordance with these proportions is to be preferred, it is of course understood that other mixtures may likewise be used within the 60 scope of the invention.

While I have herein described and upon the drawing shown an illustrated embodiment of the invention, it is to be understood that the invention is not limited thereto but may comprehend other constructions, arrangements of parts, details and features without departing from the spirit of the invention.

I claim:

1. In an electrical fuse, the combination of a 75 casing, a fusible element within said casing, and

a filling material surrounding said element including coarse and fine aggregates arranged to hold said element against lateral displacement.

2. In an electrical fuse, the combination of a 5 casing, a fusible element within said casing, and a filling material of granular particles varying in size and arranged to hold said element against lateral displacement.

3. In an electrical fuse, the combination of a 10 casing, a fusible element within said casing, and a filling material surrounding said element and including a coarse aggregate having the voids thereof filled with a finer aggregate.

4. In an electrical fuse, the combination of a 15 casing, a fusible element within said casing, and a filling material surrounding said element and including an aggregate of granular particles comprising a coarse aggregate, the voids of said coarse aggregate being filled with a finer aggregate whereby shifting of said coarse aggregate is prevented.

5. A filling material for electrical fuses, comprising an aggregate of coarse particles having the voids thereof substantially filled with particles of a finer aggregate.

6. A filling and packing material, comprising an aggregate of particles having a specific gravity substantially equal to the specific gravity of said particles.

7. A filling and packing material, comprising an aggregate of particles having a specific gravity approaching the specific gravity of said particles.

8. A filling and packing material comprising an aggregate including coarse particles, and finer particles for substantially filling the voids between said coarse particles.

9. A filling and packing material, comprising an aggregate including coarse granular particles, and finer granular particles for substantially filling the voids between said coarse particles.

10. A device for packing articles, comprising a casing, an article to be packed within said casing, and an aggregate of particles varying in size surrounding said article and adapted to arrange themselves to prevent displacement thereof when said device is moved.

11. A device for packing articles, comprising a casing, an article to be packed within said casing, an aggregate including coarse particles around said article, and finer particles for substantially filling the voids between said coarse particles to prevent shifting of said particles and displacement of said article.

12. A device for packing articles, comprising a casing, an article to be packed within said casing, an aggregate including coarse granular particles around said article, and finer granular particles for substantially filling the voids between said coarse particles to prevent shifting of said particles and displacement of said article.

13. A filling and packing material, comprising a mixture of about 70% 10-20 mesh filler, about 5% 30-40 mesh filler, and about 25% 50-60 mesh filler adapted to produce a mixture of substantially maximum specific gravity.

14. A filling and packing material, comprising an aggregate of particles of varying sizes, the size of said particles being such that the voids of each size are substantially filled by particles of smaller diameter whereby the specific gravity of said aggregate approaches the specific gravity of the particles.

15. A filling and packing material, comprising an aggregate of particles consisting of varying percentages of particles of varying sizes to pro-

vide an aggregate having a specific gravity approaching the specific gravity of the particles.

16. In an electrical fuse, the combination of a housing, a fusible element normally spaced from 5 said housing, and a filling material disposed around said element, said material comprising an aggregate of particles of varying sizes, the size of said particles being such that the voids of each 10 size are substantially filled by particles of smaller diameter whereby the specific gravity of said aggregate approaches the specific gravity of the particles and adapted to arrange themselves to prevent displacement of said element when said fuse is moved.
- 15 17. In an electrical fuse, the combination of a housing, a fusible element normally spaced from said housing, and a filling material disposed

around said element, said material comprising an aggregate of particles consisting of varying percentages of particles of varying sizes to provide an aggregate having a specific gravity approaching the specific gravity of the particles and adapted to arrange themselves to prevent displacement of said element when said fuse is moved.

18. In an electrical fuse, the combination of a housing, a fusible element normally spaced from 10 said housing, and a filling material disposed around said element, said material comprising a mixture of about 70% 10-20 mesh filler, about 5% 30-40 mesh filler, and about 25% 50-60 mesh 15 filler adapted to produce a mixture of substantially maximum specific gravity.

CLARENCE A. HERBST.
